Atty.

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed January 5, 1920. Serial No. 349,526.

My invention relates to mining apparatus. It has for its object to provide an improved apparatus especially adapted to use in cutting kerfs at a level above the mine bottom, and more especially to truck mounted apparatus adapted to cut kerfs at different levels relative to the mine bottom. A more specific object of my invention is to provide improved means for transporting, supporting, and adjusting a mining machine of the usual so-called "room and pillar" type, whereby the same may be conveniently transported from place to place and adapted to cut kerfs at varying levels in either room or entry work. These and other objects and advantages of my improved construction will, however, hereinafter more fully appear.

In the accompanying drawings I have shown, for purposes of illustration, one embodiment which my invention may assume in practice.

In these drawings,

Fig. 1 is a side elevation of this form of my invention, certain parts being shown in full and dotted lines in different positions.

Fig. 2 is a plan view of the vertically adjustable truck.

Fig. 3 is a diagrammatic plan view showing the different cuts made by the cutting mechanism.

In this illustrative construction, I have disclosed my invention as applied to use in connection with a standard form of mining machine 1, of the room and pillar type, having a feed driving member 2 and a flexible feed member 3 adapted to engage therewith in such a manner that the machine is movable relative to the feed member when mounted upon a support, as herein, or when supported directly upon the bottom, my improvements herein contemplating improved means for transporting, supporting, and adjusting such a machine.

In my improved construction it will be observed that a wheeled transport truck frame 4 is provided, herein rigidly supported on suitable upstanding supports 5, which are in turn carried on a lower frame 6 carrying suitable removable axle boxes 7 and usual truck wheels 8. Obviously, the frame 4 may, however, be carried at any suitable level with respect to the axes of the truck

wheels, the height of the same depending upon whether or not the supports 5 are used and upon the length of the supports 5 selected. Carried upon this frame 4, and herein pivotally connected thereto at its rear end on a transverse axis, as at 9, is an upper machine supporting and guiding frame 10 normally disposed in horizontal relation upon and preferably within the frame 4 and movable vertically about its pivot from that horizontal position to a plurality of inclined positions such as the inclined position shown in dotted lines in Fig. 1. This frame member 10 in turn carries at its rear end usual truck driving mechanism 11, herein for example driven from a gear 12 on the mining machine 1 and in turn operatively connected, as through a chain 13, with the truck wheels 8; and, further, is provided with a usual cable reel 14 and a usual abutment 15 to which the flexible feeding member 3 of the mining machine may be connected to move the machine longitudinally toward the rear end of the member 10.

Operatively connected to the transport truck comprising these cooperating members 4 and 10, is another or cutting truck element which is adapted to receive the mining machine from the member 10 in certain positions of this other truck element. As shown, this last mentioned truck element includes a frame 16 having a bottom plate or skid 17 removably mounted on truck wheels 18 and carrying an upper machine receiving and guiding member or slide 19 mounted for vertical adjustment relative to the frame 16 upon jack screws 20, the latter herein being disposed one at the front end of the frame and two at the rear end thereof, and arranged to be manually adjusted through movement of rotating members 21. As shown, this member 19 is carried directly on a swivel plate 22 rotatable at 23 on a corresponding lower plate 24 disposed between the same and the jack screws and supported and adjusted by the latter, a series of perforations 25 also being provided around the periphery of the plates and adapted to receive a pin 26 to lock the member 19 in any desired angular position. As shown, the plate 24 is also operatively connected to the front end of the machine supporting and guiding member 10, as for instance, through

a draw bar 27 pivotally connected at one end to the member 19 on a horizontal pivot 28 and pivoted at its opposite end to the member 10 on a vertical pivot 30. Thus it will be noted that a construction is produced which is adapted to be vertically adjusted and yet to permit the transfer of the mining machine from its supporting and guiding frame 10 in any position of the parts. It will also be noted that suitable provision is made, herein in the form of a well known latch mechanism 29 adapted to lock the machine on the member 19 and thereby enable the machine to cut when carried by said member, the same movable latch on the machine preferably also being adapted to engage the frame 10 to lock the machine thereto when in transport position.

In the use of my improved construction, the machine is carried during transport, on the power driven truck, the member 10 then preferably being disposed horizontally with respect to the track. Through its connection with the vertically adjustable truck, the power driven truck thus acts to push or drag the former about the mine. When a place is reached, the trucks are moved to the desired position in the room or entry, and then, by adjusting the members 21 of the jack screws, the member 19 is adjusted vertically into the desired vertical cutting position. During this adjustment, through the connection 27 between the member 23 and the member 10, the latter member will likewise be adjusted, about its pivot in such a manner as to form an incline always connecting the member 19 and the member 10. As a result, when the member 19 is adjusted as desired, by simply connecting the flexible feed member 3 of the mining machine to a suitable abutment at a point in advance of the machine, the latter may be caused to travel longitudinally and up the member 10 into an operative position upon the member 19, in which position the machine may be suitably locked by the latch 29. When in this position, it will be evident that through the swivel connection of the member 19, that member may be swung about its pivot as desired to insert various types of cut. For instance, it may be swung in such a manner that, when the flexible feed member is connected to the face, as shown in full lines in Fig. 3, and thereafter successively connected in well known steps (not shown), the machine may be made to cut a so-called "arcwall" cut in an entry, the machine and trucks moving toward or from the face during the usual sumping and withdrawal cuts. Conversely, when it is desired again to transport the machine about the mine, as to a different place, by simply swinging the member 19 into alinement with the member 10 and connecting the flexible feed member to the abutment 15 on the rear end of the

member 10, the machine may be fed rearward into its transport position shown in Fig. 1, and then, even while tilted slightly, if desired, propelled through the truck driving mechanism to any desired place, where cutting can be resumed at the same or a different level, as may be necessary.

As a result of my improved construction it will be observed that it is possible to adjust the kerf cutting mechanism vertically with great facility and without the necessity for providing any heavy or expensive power driven vertical adjusting means, the member 19 being vertically adjustable manually when unloaded, and by a simple and relatively easy adjustment of the jack screw members 21. Attention is also directed to the fact that the mechanism used does not in any way compel the mining machine to be dismantled or rendered incapable of use at any time as a bottom cutter, and it should also be noted that by simply removing the member 4 and supports 5 and connecting the axle boxes 7 directly to the member 10, the transport truck may likewise be readily adapted, when desired, to use in its ordinary relation. The same flexibility is also found in the vertically adjustable truck, which, when desired, may be bodily removed from its wheels and adapted to slide on its bottom plate 17 as a vertically adjustable skid slideable on the bottom and forming a support for a standard room and pillar or longwall machine, all in a well known manner. These and other advantages of my improved construction will, however, be clearly apparent to those skilled in the art.

While I have in this application specifically described one form which my invention may assume in practice, it is to be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a wheeled machine guiding element, a vertically adjustable machine support, and operative connections therebetween for tilting said element as the elevation of said support is varied.

2. In a mining apparatus, a plurality of trucks, one vertically adjustable and the other having a vertically tiltable portion, and means for tilting said portion as the first truck is adjusted.

3. In a mining apparatus, a transport truck having a tiltable machine guiding portion, a cutting truck having a vertically adjustable machine receiving portion, and operative connections between said trucks.

4. In a mining apparatus, a transport truck having a tiltable machine guiding por-

- tion, a cutting truck having a vertically adjustable machine receiving portion, and a draw bar pivotally connected between said portions.
5. In a mining apparatus, a transport truck having a tiltable machine guiding portion, a cutting truck having a vertically adjustable portion, and means for tilting said tilting portion as said vertically adjustable portion is adjusted.
10. In a mining apparatus, a transport truck having running gear and adapted to support a mining machine during running around a mine, a cutting truck having running gear and adapted to support a mining machine during the cutting operation, the running gear of said trucks being guided by the same trackway, and machine guiding means extending between said trucks for transferring a mining machine off of either of said trucks onto the other.
15. In a mining apparatus, a transport truck adapted to transport a mining machine during running around a mine, a cutting truck adapted to support and to move bodily with a mining machine during the cutting operation and having machine receiving portions disposable in a plurality of different positions relative to other portions of said truck, and means for transferring a mining machine off of either of said trucks onto the other in different positions of said machine receiving portion of said cutting truck.
20. In a mining apparatus, a transport truck adapted to support a mining machine during running around a mine, a cutting truck adapted to support and to move bodily with a mining machine during the cutting operation, and means for transferring a mining machine off of either of said trucks onto the other when said cutting truck is at a different elevation from said transport truck.
25. In a mining apparatus, a transport truck, a vertically adjustable cutting truck, and means including a machine guiding frame extending between and connected to said trucks for transferring a mining machine between said trucks in different vertical positions of the latter truck.
30. In a mining apparatus, a transport truck, a cutting truck, manually operable means for varying the elevation of the latter, and means including a machine guiding frame extending between and connected to said trucks for thereafter transferring a mining machine from said transport truck to said cutting truck.
35. In a mining apparatus, a cutting truck, a mining machine support thereon, a mining machine, manually operable means for vertically adjusting said support, means for thereafter feeding said mining machine onto said support under its own power, and power operated means for moving said machine and truck along a trackway during the cutting operation.
40. In a mining apparatus, a cutting truck, manually operable means for vertically adjusting the same, a transport truck, and a pivotally connected guiding frame thereon angularly adjustable as said cutting truck is adjusted.
45. In a mining apparatus, a rigid upstanding transport truck, and a mining machine receiving and guiding frame thereon including means for slidably receiving a unitary mining machine during loading and unloading thereof, said frame being normally disposed in horizontal relation and tiltable relative to said truck about a horizontal axis to elevate its front end above the horizontal.
50. In a mining apparatus, a transport truck, and a normally horizontally disposed mining machine receiving and guiding frame thereon including means for slidably receiving a unitary mining machine during loading and unloading thereof, said frame being tiltable about a horizontal axis at the rear end of said truck to elevate its front end above the horizontal.
55. In a mining apparatus, a wheeled transport truck, a machine receiving frame pivoted on a transverse axis on the rear end thereof, and wheel driving mechanism on said machine receiving frame.
60. In a mining apparatus, a wheeled transport truck, a machine receiving frame pivoted on a transverse axis on the rear end thereof, and wheel driving mechanism on said machine receiving frame in rear of said pivot.
65. In a mining apparatus, a transport truck including a horizontal frame member, upstanding supports beneath the same, and wheels beneath said supports, and a machine receiving member pivoted on a transverse axis on said horizontal member, said receiving member overlying said horizontal frame member and adapted to slidably receive a unitary mining machine during loading and unloading thereof.
70. In a mining apparatus, a cutting truck, manually operable means for vertically adjusting the same, a transport truck, and a pivotally connected guiding frame thereon angularly adjustable as said cutting truck is adjusted.
75. In a mining apparatus, a rigid upstanding transport truck, and a mining machine receiving and guiding frame thereon including means for slidably receiving a unitary mining machine during loading and unloading thereof, said frame being normally disposed in horizontal relation and tiltable relative to said truck about a horizontal axis to elevate its front end above the horizontal.
80. In a mining apparatus, a transport truck, and a normally horizontally disposed mining machine receiving and guiding frame thereon including means for slidably receiving a unitary mining machine during loading and unloading thereof, said frame being tiltable about a horizontal axis at the rear end of said truck to elevate its front end above the horizontal.
85. In a mining apparatus, a transport truck, and a normally horizontally disposed mining machine receiving and guiding frame thereon including means for slidably receiving a unitary mining machine during loading and unloading thereof, said frame being tiltable about a horizontal axis at the rear end of said truck to elevate its front end above the horizontal.
90. In a mining apparatus, a wheeled transport truck, a machine receiving frame pivoted on a transverse axis on the rear end thereof, and wheel driving mechanism on said machine receiving frame.
95. In a mining apparatus, a wheeled transport truck, a machine receiving frame pivoted on a transverse axis on the rear end thereof, and wheel driving mechanism on said machine receiving frame.
100. In a mining apparatus, a wheeled transport truck, a machine receiving frame pivoted on a transverse axis on the rear end thereof, and wheel driving mechanism on said machine receiving frame in rear of said pivot.
105. In a mining apparatus, a transport truck including a horizontal frame member, upstanding supports beneath the same, and wheels beneath said supports, a machine receiving member pivoted on a transverse axis on said horizontal member, said receiving member overlying said horizontal frame member and adapted to slidably receive a unitary mining machine during loading and unloading thereof.
110. In a mining apparatus, a transport truck including a horizontal frame member, upstanding supports beneath the same, and wheels beneath said supports, a machine receiving member pivoted on a transverse axis on said horizontal member, and wheel driving mechanism on said pivoted member.
115. In a mining apparatus, a transport truck including a horizontal frame member, upstanding supports beneath the same, and wheels beneath said supports, a machine receiving member pivoted on a transverse axis on said horizontal member, and wheel driving mechanism on said pivoted member.
120. In a mining apparatus, a truck comprising a wheeled frame, a vertically adjustable portion thereon, a machine receiving member swivelly mounted on said vertically adjustable portion for pivotal movement relative thereto upon a vertical axis and during transport disposed longitudinally of said truck, means for holding said swiveled member in different angular posi-

- tions, a unitary mining machine carried by said member, and means for fixing said machine on said member.
20. In a mining apparatus, a truck comprising a wheeled frame, a vertically adjustable portion thereon, means acting on said vertical axis portion at three substantially spaced points for adjusting the same vertically, a machine receiving member 10 swivelly mounted on said vertically adjustable portion and during transport disposed longitudinally of said truck, means for holding said swiveled member in different angular positions, a unitary mining machine carried by said member and means for fixing said machine on said member.
21. In a mining apparatus, a truck comprising a wheeled frame, a vertically adjustable portion thereon, means for adjusting the same vertically, a machine receiving slide swivelly mounted on said vertically adjustable portion for pivotal movement relative thereto upon a vertical axis and during transport disposed longitudinally of 25 said truck, means for holding said swiveled slide in different angular positions, a mining machine receivable in said slide and disposed longitudinally thereof and means for fixing said machine on said slide.
22. In a mining apparatus, a truck comprising a wheeled frame, a vertically adjustable portion thereon, a machine carrying member swiveled on said portion for pivotal movement relative thereto upon a vertical axis, means for holding said member in different angular positions, a complete mining machine carried on said carrying member, and means operated by said machine for 35 swinging said swiveled member relative to said adjustable portion and for moving said machine and truck bodily along a trackway.
23. In a mining apparatus, a truck comprising a wheeled frame, a vertically adjustable portion thereon, a machine carrying member swiveled on said portion for pivotal movement relative thereto upon a vertical axis, means for holding said member in different angular positions, a complete mining machine carried on said carrying member, and means for fixing said mining machine 45 thereon.
24. In a mining apparatus, a truck comprising a wheeled frame, a vertically adjustable portion thereon for pivotal movement relative thereto upon a vertical axis, a machine receiving member swiveled on said portion, means for holding said member in different angular positions, a complete mining machine carried on said receiving member and latching mechanism between said receiving member and machine.
25. In a mining apparatus, a truck comprising a wheeled frame, a vertically adjustable portion thereon, a machine carrying member swiveled on said portion for pivotal 60
- movement relative thereto upon a vertical axis, a complete mining machine carried on said carrying member including a flexible feeding member, and means operated by said flexible member for swinging said machine 70 and swiveled member during the cutting operation.
26. In a mining apparatus, a truck comprising a wheeled frame, a vertically adjustable portion thereon, a machine carrying member swiveled on said portion for pivotal movement relative thereto upon a vertical axis, means for holding said member in different angular positions, a complete mining machine carried on said carrying member including a flexible feeding member, and means operated by said flexible member for swinging said swiveled member relative to said adjustable portion and for moving said machine and truck bodily along a trackway. 75
27. In a mining apparatus, a plurality of operatively connected wheeled trucks, a unitary mining machine, operative connections whereby said mining machine may be moved relative to the wheels of one of said trucks under its own power while cutting, power operated means for moving the machine and truck along a trackway while cutting, and operative connections whereby the wheels of said other truck may be driven by the power of said mining machine during transport. 80
28. In a mining apparatus, a truck comprising wheels, a frame, an intermediate spacing means, and a cooperating operatively connected truck comprising wheels, a skid, machine carrying means on said skid, said trucks having provision whereby when disconnected said frame may be carried at will directly on said wheels and whereby said cooperating truck may slide on the bottom 85 on its skid when said trucks are disconnected, and machine guiding means extending between said trucks and connected thereto for guiding a mining machine for movement from one truck to the other. 100
29. In a mining apparatus, a skid, a vertically adjustable portion carried thereon, a swiveled mining machine carrying member carried on said vertically adjustable portion for pivotal movement relative thereto upon a vertical axis, means for holding said member in different angular positions, a unitary mining machine on said swiveled member, and means for fixing said mining machine 105 on said swiveled member.
30. In a mining apparatus, a skid, a vertically adjustable portion carried thereon, a swiveled mining machine carrying member carried on said vertically adjustable portion for pivotal movement relative thereto upon a vertical axis, means for holding said member in different angular positions, a unitary mining machine carried on said member, and means for fixing said machine thereto. 115
31. In a mining apparatus, a skid, a verti- 120
- 125
- 130

- 5 cally adjustable portion carried on said skid, manually operable means for adjusting the same, a swiveled mining machine receiving slide carried on said vertically adjustable portion for pivotal movement relative thereto upon a vertical axis, and wheels removably attached to said skid. 70
- 10 32. In a mining apparatus, a skid, a vertically adjustable portion carried on said skid, manually operable means for adjusting the same, a swiveled mining machine receiving slide carried on said vertically adjustable portion, means for locking the same in a plurality of angular positions, and wheels 75 removably attached to said skid. 15
- 20 33. In a mining apparatus, an elevated transport truck, a cutting truck having a vertically adjustable support thereon, a machine guiding member pivotally mounted on said transport truck on a horizontal axis, a machine receiving slide swiveled on said vertically adjustable support, and means between said guiding member and said support for tilting the former about its pivot as the 80 25 elevation of said support is varied. 25
- 30 34. In a mining apparatus, an elevated transport truck, a cutting truck having a vertically adjustable support thereon, a machine guiding member pivotally mounted on said transport truck on a horizontal axis, a machine receiving slide swiveled on said vertically adjustable support, means between said guiding member and said support for tilting the former about its pivot as the elevation of said support is varied, and a mining 85 35 machine having provision for propelling itself between said guiding member and said slide. 35
- 40 35. In a mining apparatus, an elevated wheeled transport truck, a cutting truck having a vertically adjustable support thereon, a machine guiding member pivotally mounted on said transport truck on a horizontal axis, a machine receiving slide swiveled on a vertical axis on said vertically adjustable support, means between said guiding member and said support for tilting the former about its pivot as the elevation of said support is varied, a mining machine 90 45 normally carried on said machine guiding member having provision for propelling itself between said guiding member and said slide, and wheel driving mechanism operatively connected to the wheels of said transport truck and carried on said machine guiding member adapted to be driven by said mining machine. 50
- 55 36. In a mining apparatus, a wheeled machine guiding element, a wheeled vertically adjustable machine support, and operative connections therebetween for tilting said element as the elevation of said support is varied. 60
- 60 37. In a mining apparatus, a wheeled transport truck, a wheeled cutting truck, the wheels 65 of said truck being adapted to run along the same trackway, means for transferring a mining machine from one truck to the other, and means for locking said machine in operative position on either of said tracks. 70
- 70 38. In a mining apparatus, a wheeled transport truck, a wheeled cutting truck, the wheels of said truck being adapted to run along the same trackway, means for transferring a mining machine from one truck to the other, and means for utilizing the power of said machine for moving either of said trucks. 75
- 80 39. In a mining apparatus, a truck comprising a wheeled frame, a vertically adjustable portion thereon, a mining machine carrying member swiveled on said portion, means for holding said member in different angular positions, and a complete mining machine of a bottom cutting type including a cutter bar and means operative to swing said bar during cutting or to move said truck longitudinally of the trackway during cutting on said portion. 85
- 85 40. In a mining apparatus, a truck comprising a wheeled frame, a vertically adjustable portion thereon, a mining machine carrying member swiveled on said portion, means for holding said member in different angular positions, a complete mining machine of a bottom cutting type including a cutter bar and means operative to swing said bar during cutting or to move said truck longitudinally of the trackway during cutting, and truck wheel driving mechanism operatively connectible to said mining machine 90 during transport. 95
- 90 41. In a mining apparatus, a truck comprising a wheeled frame, a vertically adjustable portion thereon, a kerf cutter carrying member swiveled on said portion for pivotal movement relative thereto upon a vertical axis, means for holding said member in different angular positions, kerf cutting mechanism thereon and movable horizontally rectilinearly relative thereto including a cutter bar and means operative to swing said member during cutting or to move said truck longitudinally of a trackway during cutting, and truck wheel driving mechanism operatively connectible to said kerf cutter during transport. 100 105
- 105 42. In a mining apparatus, a truck comprising a wheeled frame, a vertically adjustable portion thereon, nut and screw connections for adjusting said portion, a machine receiving member swivelly mounted on said vertically adjustable portion for pivotal adjustment relative thereto on a vertical axis, a mining machine carried by said member and slidably rectilinearly horizontally relative thereto, and means operated by said machine for swinging said swiveled member relative to said adjustable portion. 110 115
- 115 43. In a mining apparatus, a wheeled 120
- 120
- 125
- 130

transport truck including means receiving a mining machine for transport, a second wheeled truck having means for receiving said mining machine from said first mentioned truck preliminary to cutting, and machine guiding means pivotally connecting said trucks.

44. In a mining apparatus, a cutting truck, a mining machine support thereon, means for vertically adjusting said support including pairs of cooperating relatively rotatable threaded members, one member of each pair being rotatable to effect longitudinal movement of the other member of its respective pair, said other members of said pairs moving with said support while the latter moves relative to the first mentioned members of said pairs, a mining machine having cutting mechanism, and means for feeding said mining machine onto said support under its own power after adjustment of said support, said machine moving onto said support at the end thereof opposite that from which its cutting mechanism operates.

45. In a mining apparatus, a wheeled frame, a supporting frame vertically adjustable relatively to said frame, a turntable mounted on said supporting frame, a mining machine guiding frame mounted on said turntable adapted to slidably receive a unitary mining machine, and a mining machine having power operated feeding mechanism for moving the same relative to said guiding frame.

46. In a mining apparatus, a wheeled frame, a supporting frame vertically adjustable relatively to said frame, a turntable mounted on said supporting frame, a machine guiding frame pivotally connected on said turntable adapted to slidably receive a unitary mining machine during loading and unloading thereof, and a mining machine having feeding mechanism for moving the same relative to said guiding frame and for swinging said guiding frame on said turntable.

47. In a mining apparatus, a wheeled truck frame, and a guiding frame thereon adapted to slidably receive a unitary mining machine of the type adapted to slide during cutting directly on a mine bottom and tiltable at its rear end about a relatively fixed horizontal axis to elevate the front end thereof of above the horizontal.

48. In a mining apparatus, the combination of a wheeled truck frame, a guiding frame thereon adapted to slidably receive a unitary mining machine during loading and unloading thereof, and means operatively connected to said wheeled truck frame whereby said machine may be supported independently of said guiding frame in different elevated positions during cutting.

49. In a mining apparatus, a truck com-

prising a wheeled frame, a mining machine support thereon, guiding means on said support for slidably receiving a mining machine, a unitary mining machine carried by said guiding means, means for fixing said machine on said guiding means, and means for vertically adjusting said support relatively to said frame independently of said mining machine including pairs of cooperating relatively rotatable threaded members, one member of each pair being rotatable to effect longitudinal movement of the other element of its respective pair and said other members moving with said support while the latter moves relative to said first mentioned members of each pair.

50. In a mining apparatus, a truck comprising a wheeled frame, a support thereon, guiding means on said support for slidably receiving a mining machine, a unitary mining machine on said guiding means, means for fixing said machine on said guiding means, means for vertically adjusting said support relatively to said frame including pairs of cooperating relatively rotatable threaded members, one member of each pair being rotatable to effect longitudinal movement of the other element of its respective pair and said other members moving with said support while the latter moves relative to said first mentioned members of each pair, and means for feeding said mining machine on to said support after said vertical adjustment has been made.

51. In a mining apparatus, a truck comprising a wheeled frame, a support thereon including a pivoted guiding frame portion adapted to slidably receive a unitary mining machine, a mining machine carried on said guiding frame, means for fixing said machine on said guiding frame, means for holding said guiding frame in different angular positions, means for vertically adjusting said support relatively to said wheeled frame including pairs of cooperating relatively rotatable threaded members, one member of each pair being rotatable to effect longitudinal movement of the other element of its respective pair and said other members moving with said support while the latter moves relative to said first mentioned members of each pair, and means for feeding said mining machine on to said support after said vertical adjustment has been made.

52. In a mining apparatus, a truck comprising a wheeled frame, a support thereon, guiding means on said support for slidably receiving a mining machine, a unitary mining machine removably carried on said guiding means, means for fixing said machine on said guiding means, means for vertically adjusting said support relatively to said frame independently of said mining machine including pairs of cooperating relatively ro-

tatable threaded members, one member of each pair being rotatable to effect longitudinal movement of the other element of its respective pair and said other members moving with said support while the latter moves relative to said first mentioned members of each pair, and means for feeding said machine longitudinally from said support.

5 53. In a mining apparatus, a truck comprising a wheeled frame, a support thereon including a pivoted machine guiding frame, a unitary mining machine removably carried on said support, means for fixing said machine on said guiding frame, means for 10 holding said guiding frame in different angular positions, means for vertically adjusting said support relatively to said guiding frame independently of said mining machine including pairs of cooperating relatively 15 rotatable threaded members, one member of each pair being rotatable to effect longitudinal movement of the other element of its respective pair and said other members moving with said support while the latter moves 20 relative to said first mentioned members of 25

each pair, and means for feeding said mining machine longitudinally from said support.

54. In a mining apparatus, a truck comprising a wheeled frame, a support swivelly 30 mounted thereon, a unitary mining machine removably carried on said support, means for fixing said mining machine on said support, means for holding said support in different angular positions, means for vertically adjusting said support relatively to said frame independently of said mining machine including pairs of cooperating relatively 35 rotatable threaded members, one member of each pair being rotatable to effect longitudinal movement of the other element of its respective pair and said other members moving with said support while the latter moves relative to said first mentioned members of each pair, and means for feeding 40 said machine bodily from said support when the latter is disposed in different angular positions relatively to said truck frame.

In testimony whereof I affix my signature.
MORRIS P. HOLMES.

CERTIFICATE OF CORRECTION.

Patent No. 1,664,384.

Granted March 27, 1928, to

MORRIS P. HOLMES.

It is hereby certified that error appears in the printed specification of the above numbered patent requiring correction as follows: Page 4, lines 54 and 55, claim 24, strike out the words "for pivotal movement relative thereto upon a vertical axis"; same page and claim, line 57, after the word "portion" insert a comma and the words "for pivotal movement relative thereto upon a vertical axis"; page 5, line 20, claim 33, for the misspelled word "hornzontal" read "horizontal", and line 70, claim 37, for the word "tracks" read "trucks"; and that the said Letters Patent should be read with these corrections therein that the same may conform to the record of the case in the Patent Office.

Signed and sealed this 29th day of May, A. D. 1928.

(Seal)

M. J. Moore,
Acting Commissioner of Patents.
